MICROPHONE

Robert Podall, Northfield, Ill., assignor to Conrac Corporation, New York, N.Y.

Filed Jan. 14, 1971, Ser. No. 106,620

Term of patent 14 years

Int. Cl. D14—01

U.S. Cl. D26—14

FIG. 1 is a perspective of the front, top and left side of a microphone illustrating my new design.

FIG. 2 is a side elevation showing the right side thereof.

FIG. 3 is a rear elevation thereof.

FIG. 4 is a bottom view thereof.

I claim:

The ornamental design for a microphone, as shown and described.
